(57) **CLAIM**

The ornamental design for a training bat, as shown and described.

DESCRIPTION

FIG. 1 is a perspective view of a training bat of the present disclosure;

FIG. 2 is a front view of the training bat of FIG. 1; the undisclosed rear view being a mirror image;

FIG. 3 is a perspective view of a second embodiment of the training bat;

FIG. 4 is a front view of the training bat of FIG. 3; the undisclosed rear view being a mirror image;

FIG. 5 is a perspective view of a third embodiment of the training bat;

FIG. 6 is a front view of the training bat of FIG. 5; the undisclosed rear view being a mirror image;

FIG. 7 is a perspective view of a fourth embodiment of the training bat;

FIG. 8 is a front view of the training bat of FIG. 7; the undisclosed rear view being a mirror image;

FIG. 9 is a perspective view of a fifth embodiment of the training bat;

FIG. 10 is a front view of the training bat of FIG. 9; the undisclosed rear view being a mirror image;

FIG. 11 is a perspective view of a sixth embodiment of the training bat; and,

FIG. 12 is a front view of the training bat of FIG. 11; the undisclosed rear view being a mirror image.

The undisclosed left, right, top and bottom views form no part of the claim design.

The training bats of FIGS. 1-4 are of a first length, the training bat of FIGS. 5 and 6 is of a second length, the training bat of FIGS. 7 and 8 is of a third length, the training bat of FIGS. 9 and 10 is of a fourth length, and the training bat of FIGS. 11 and 12 is of a fifth length.

The dash-dot-dash broken lines represent boundary lines and form no part of the claimed design.
